UNITED STATES PATENT OFFICE

2,519,303

SAMPLING DEVICE

Ben Whitehouse, Milwaukee, Wis., assignor to
 Rodwell Engineering and Sales Company,
 Omaha, Nebr.

Application June 2, 1947, Serial No. 751,763

2 Claims. (Cl. 73—422)

1

My invention relates to sampling devices and more particularly to a device for permitting a small quantity of liquid under pressure to be dispensed for testing purposes.

It is manifest to anyone familiar with the operation of high or low pressure steam boilers, or hot water heating boilers, that it is desirable and, in fact, imperative that periodic tests be made to determine the condition of the water in the system. It is difficult to obtain a truly representative sample from the boiler, due to the danger of unequal distribution of the sedimentation or sludge which collects at the bottom of the boiler, if there is not sufficient agitation by circulation provided, and it is quite necessary to include all the impurities contained in the water when obtaining a truly representative sample.

The object of my invention is to provide a device that may be attached to a pipe line through which the water is being circulated while the water is thoroughly agitated and having the sludge and impurities suspended therein, together with the chemicals for water treatment and other materials carried in solution.

Another object of my invention is to provide such a device that will in no manner affect the pressure maintained in the boiler or pipe line.

A still further object of my invention is to provide a device that may be installed within the circulating line to the filter in the blow-off line of the water column, or in the continuous blow-off line, and will prevent the formation of flash steam which destroys a truly representative sample, and interferes with the draining of the sample.

Still another object of my invention is to construct a device that may be placed in the pipe line with ease, and without the necessity of a number of mechanical changes, thereby providing a device that is economical to construct and install.

With the foregoing and other objects in view which will be made known in the following description, the device is illustrated in the accompanying drawings in which

Figure 1 is a cross-sectional view of the device showing the arrangement of the various valves and leads, with the device inserted into a pipe line such as a line leading from the boiler to a filter.

Figure 2 is a cross-sectional fragmentary view of the device with the valves arranged for normal operation, and

Figure 3 is a view similar to Figure 2 in which the valves of the device are arranged for draining a sample of the water being circulated.

Similar characters of reference indicate corresponding parts throughout the several views, and referring now to the same, the character 10 shows a pipe line in the water system of a high or

2

low pressure steam boiler or hot water heating boilers. This pipe line 10 may be provided with the necessary valves as shown at 11 at the upper inlet end as well as the valve 12 at the lower outlet end of a portion of the line 10. There is a cold water jacket indicated by the character 13 which surrounds a portion of the pipe line 10 and is shown welded at its top and bottom 14 and 14' respectively.

The jacket 13 has a cold water inlet 15 at its upper end and a drain 17 near its lower end provided with a valve 18, and the pipe line 10 is equipped with a drain 19 shown provided with a spigot or pet cock 20 below the water jacket 13.

Obviously, if the pipe line 10 extends from the boiler skimmer to a filter or to a boiler water column blow-off or continuous blow-off, the water in the pipe 10 is truly representative of the type of water within the boiler. Thus when installed in a continuous blow-off line, or a line from the boiler to the filter, in either case while in operation, to obtain a sample of the water for analysis it is only necessary to close the valve 12. Next open the valve 16, thereby permitting cold water to circulate through the jacket 13 which surrounds a portion of the pipe 10.

Before taking a sample of the water within the portion of the pipe line 10 surrounded by the jacket 13, it is necessary to crack the valve 20 to a point where flash steam forms and residual solids etc. have been discharged, and then close the valve until just a dribble of water discharges, which means that the flash steam and solids have been eliminated and the temperature of the water within the pipe line 10 is decreased to a temperature of 212° F. or below. It is then necessary to let the water flow out of the pet cock 20 in a steady even stream and take this water as a sample, for at the temperature brought down by the cold water through the means provided by the jacket 13 surrounding that portion of the pipe 10, it will be a truly representative sample of the boiler water with the sludge particles and solids suspended therein, together with the chemicals of the water treatment and other materials held in solution.

The arrangement of the valves during this procedure is illustrated in a diagram shown in Figure 3, while the valves as shown in Figure 2 show the normal arrangement during the continuous operation of the boiler, continuous blow-off or water filter.

In the chosen embodiments of my invention exemplified by the foregoing description there are present many features not heretofore disclosed in the prior art. However, I have shown a particular arrangement of the component parts, but am fully cognizant of the fact that many changes in the form and configuration of the component parts may be made without effecting

their operativeness, and I reserve the right to make such changes as I may deem convenient or necessary without departing from the spirit of my invention or the scope of the appended claims.

Having thus described my invention, what I claim and desire to secure by Letters Patent in the United States is:

1. A device of the character described comprising a pipe line provided with a drain cock, a water jacket surrounding a portion of said pipe line above said drain cock, said jacket provided with inlet and outlet tubes equipped with valves, suitable valves within said pipe line above said jacket, and below said cock, means for supplying cold water within said jacket for cooling the contents retained in that portion of the pipe line when the lower valve is closed, and enabling a sample of the contents of the pipe line to be drained through said drain cock when the temperature of said contents has been lowered by the cold water in said jacket.

2. A liquid sampling device of the character described comprising a portion of a pipe line leading from a reservoir containing an element 25 at high temperature under pressure, said pipe line provided with suitable valves at its upper

and lower end, a water jacket surrounding a portion of said pipe line between said valves, said jacket provided with a cold water inlet and outlet, said inlet and outlet provided with suitable valves for controlling said cold water, a drain cock disposed through the walls of said pipe line at a point below said jacket and above the lower valve in said pipe line, thereby providing a means of draining a portion of the contents of said pipe line when the lower valve thereof is closed and the temperature of the contents of that portion of said pipe line surrounded by said jacket has been lowered.

BEN WHITEHOUSE.
